UNITED STATES PATENT OFFICE.

PHILEBERT A. HAEVERS, OF GREEN BAY, WISCONSIN.

SILO.

1,331,195.

Specification of Letters Patent. Patented Feb. 17, 1920.

Application filed February 14, 1918. Serial No. 217,108.

To all whom it may concern:

Be it known that I, PHILEBERT A. HAEVERS, a citizen of the United States of America, residing at Green Bay, in the county of Brown and State of Wisconsin, have invented certain new and useful Improvements in Silos, of which the following is a specification, reference being had therein to the accompanying drawing.

10 The invention relates to silos, and particularly to those constructed of wood.

In the construction of wooden silos, the method hitherto adopted consisted in forming a plurality of wooden rings or hoops which were made up from a number of thin strips or laminæ of wood bent to a circle and nailed together so as to retain circular form. The hoops of course had a smaller diameter at the inside than at the outside, so

20 that in order to effect a smooth abutment between contiguous strips it was necessary to cut down the strip composed of laminæ in order to obtain a true circular form thereof.

After the somewhat tedious procedure of forming such a plurality of hoops, they were employed as spacers between the inner and outer walls or sheathings of the silo, which were nailed to the hoops. This construction entailed the formation of a dead air

30 space between the walls of the silo, whereby rapid decay of the sheathing took place.

The present invention has for its principal object the construction of silos eliminating the disadvantages hitherto accompanying

35 and inherent in silos of known construction.

It is an object of the invention to provide a silo devoid of a dead air space and therefore instead to provide for the free circulation of air between the inner and outer walls

40 thereof.

It is also an object of the invention to eliminate waste of lumber which always occurred in the construction of the ordinary silo.

45 A further object aims at the provision of means for inducing circulation of air.

It is also an object of the invention to provide a silo which can be cheaply and efficiently constructed, requiring less time to

50 complete the same than was hitherto necessary in the building of wooden silos.

A preferred embodiment of the inven-

tion is illustrated in the accompanying drawing, in which—

Figure 1 is an elevation of the silo constructed according to the invention, a portion of the outer wall being broken away to disclose the interior construction;

Fig. 2 is an enlarged elevation of a portion of the spiral spacer, the outline of the walls being shown in dotted lines;

Fig. 3 is a longitudinal section through the discharge doors of the silo, and

Fig. 4 is a section near the roof, disclosing means for inducing circulation between the silo sheathings.

In the present invention the formation of rings to act as spacers between the inner and outer walls of the silo is dispensed with and instead a plurality of laminæ or strips are arranged similarly as in the construction of hoops. In the present case, however, no hoops are constructed but a spirally continuous strip, thus dispensing with the necessity of shaping or cutting down the ends or strips in order to provide a fit such as arises in the construction of circular bodies or hoops. The spacer in the new form can of course be completed in considerably less time, as pieces of variable length may be employed and no other cutting down or trimming is required than that of providing straight ends at the top or bottom of the silo, as will be readily understood.

Referring to the drawing, 1 generally designates the silo which is formed with an outer wall or sheathing 2 and an inner wall or sheathing 3 spaced therefrom a distance equal to the thickness of a spacer 4. The latter is composed of a plurality of strips or laminæ 5 of wood, which, as explained hereinbefore, are in the form of a spiral curve and extend from the bottom of the silo to the top thereof. The silo is erected on a base 6 and the lowermost end thereof is closed up by a bottom hoop 7. The provision of the spacer 4 creates a compartment between the walls of the silo through which an air current may pass in a spiral path, and means is provided for inducing a draft when the danger is present that the contents of the silo, in view of a possible low temperature, may freeze. A pipe 8 is provided, which extends above the roof 9 in vertical direc-

tion, projects downwardly therethrough, as indicated in Fig. 4, and terminates in an elbow 10 secured to the inside wall of the silo. An opening 12 places the pipe 8 in communication with the topmost space between the walls of the silo, so that an air current starting at the bottom will pass in a serpentine path between the walls of the silo and will finally escape through the opening 12 into the pipe 10 and thence into the atmosphere.

Longitudinally of the silo, in the form of a vertical tier, a plurality of discharge doors 13 are provided for the purpose of permitting access to the interior of the silo. As is plainly indicated in Fig. 1, each door 13 is hinged at one side, as at 14, to the outer wall of the structure, and the other side is equipped with a latch 15 adapted to secure the door to a hook 16 provided on the outer wall of the silo. In horizontal registry with the outer door and substantially coextensive therewith, the inner door 17 is arranged, which forms the closure of an opening 18 provided in the inner wall 3 of the silo. The door 17 is equipped at its outer side with an enlargement 18' constituting a handle, whereby removal and insertion of the door 17 is facilitated. At the inner side 25 a member 19 is secured to the top, which is adapted to be supported by a pair of holders 20 secured at each side of the door to the inner wall 3.

As is clearly indicated, the upper edge of the opening 18 is beveled, thereby permitting elevating or raising of the door 17 when it is intended to remove the latter prior to effecting a discharge of the contents of the silo. The latter is also provided with a dormer 21, through which the silo is charged. The vertical tier of doors is arranged to open into the barn in connection with which the silo is constructed, as will be readily understood by those versed in the art.

The improved silo affords a convenient means for inducing a natural draft through the space between the walls thereof, and this is taken advantage of when, by virtue of a low prevailing temperature, the danger is present that the contents of the silo are liable to freeze. To accomplish this end the lower doors 13 are opened, whereby the warm air contained in the barn may enter the space between the walls and then rise in the predetermined path until it finally is discharged through the pipe 8 into the atmosphere. The circulation of the warm air will of course have a tendency to heat the contents of the silo and will prevent freezing thereof so as to eliminate any harmful effects thereon.

Silos are used for varied and diverse purposes. The material to be stored is packed

tightly in the silo through the dormer 21, 65 and is stored in such packed condition until discharge is desired. The discharge is effected by virtue of the discharge doors 13, each of which is arranged in juxtaposition, with an inner door permitting access to the 70 interior of the silo.

While the drawing illustrates the preferred embodiment of the invention various changes and alterations are included which fall within the scope of the invention as defined by the appended claims.

I claim:—

1. A silo having an inner and outer wall in spaced relation, a spiral spacer arranged between said walls, said spacer composed of a plurality of laminæ, a plurality of doors adapted to establish communication between the atmosphere and the space at predetermined levels, and means for establishing continuous communication between the topmost space and the atmosphere.

2. A silo having an inner and outer wall in spaced relation, a spacer of spiral form arranged in said space, said spacer having a thickness equal to the distance between said walls and forming a continuous structure, said spacer composed of a plurality of laminæ parts of various lengths, a vertical tier of doors adapted to establish communication between the space and the atmosphere at predetermined levels, and means for establishing permanent communication between the topmost portion of said space and the atmosphere.

3. A silo having an inner and outer wall in spaced relation, a spacer of spiral form arranged in said space, said spacer having a thickness equal to the distance between said walls and forming a continuous structure, said spacer composed of a plurality of laminæ of spiral form and of various lengths, a vertical tier of doors adapted to establish communication between the space and the atmosphere at predetermined levels, and a pipe opening into the top of said space 110 and being in communication with the atmosphere.

4. The combination in a silo with its inner and outer walls, of a spiral spacing element between said walls and extending through its height, said silo having a vertically arranged door space and two tiers of doors in said space arranged in pairs, one of said tiers openable to give access to the interior of the silo, and the other tier openable to permit air currents to enter the spiral space between the walls formed by the spacing element, and ventilating means through the top of the silo at the upper end of said space.

5. The combination in a silo with the outer and inner spaced walls of a spiral spacing element extending through the height of the silo between said walls and forming a contin-

uous spiral air space, a vent pipe terminal for said space supported at the top of the silo, two tiers of doors arranged in the silo, in pairs and alined with the spiral air space, 5 the inner tier of doors being openable to give access to the interior of the silo, and the outer tier of doors openable to establish

communication between the atmosphere and said spiral space at any selected altitude of the silo.

In testimony whereof I hereunto affix my signature.

PHILEBERT A. HAEVERS.
